UNITED STATES PATENT OFFICE.

WARREN P. LOUDON, OF WILKINSBURG, PENNSYLVANIA, ASSIGNOR TO WESTINGHOUSE ELECTRIC & MANUFACTURING COMPANY, A CORPORATION OF PENNSYLVANIA.

SWITCHING MECHANISM.

Application filed August 6, 1920. Serial No. 401,670.

To all whom it may concern:

Be it known that I, WARREN P. LOUDON, a citizen of the United States, and a resident of Wilkinsburg, in the county of Allegheny and State of Pennsylvania, have invented a new and useful Improvement in Switching Mechanisms, of which the following is a specification.

My invention relates to switching mechanisms, and, particularly, to switching mechanisms for controlling the ignition and lighting circuits of automobiles.

The object of my invention is to provide a switching mechanism that shall have two rotatable switch drums coaxially mounted and that shall be provided with means for locking one of the switch drums only in the "Off" position and for preventing movement of the second switch drum from any occupied position when the first switch drum is in any position.

In operating an automobile, it is desirable to lock the ignition switch in the "Off" position and to prevent operation of the lighting switch from any occupied position when the ignition switch is locked in the "Off" position. Moreover, it is desirable to prevent operation of the lighting switch from any occupied position when the ignition switch is in an operative position. Thus, when an automobile is parked, it is desirable to have the ignition switch locked in its "Off" position and to prevent operation of the lighting switch either from the "Off" position or from any operative position, according to the time of day. Moreover, it is desirable to prevent operation of the lighting switch from any of its operative positions when the ignition switch is in an operative position.

In a switching mechanism constructed in accordance with my invention, the ignition switch can be locked in its "Off" position and the lighting switch drum can be disconnected from its operating handle to prevent operation of the lighting switch from any position. Thus, movement of the lighting switch may be prevented either from its "Off" position or from any of its operative positions. The position of the ignition switch in no way prevents the operation of the means for disconnecting the lighting switch drum from its operating handle.

In the preferred embodiment of my invention, the ignition switch and the lighting switch each comprise a contact drum. The

contact drums have the same axis of rotation and a suitable handle is provided for operating each of the drums. A lock mechanism is provided for locking the ignition drum in the "Off" position and for disconnecting the lighting drum from its associated handle in any position of such lighting drum. The ignition drum is provided with a recess and a pin or block member, which is under the control of the lock mechanism, is adapted to enter such recess and prevent movement of the ignition switch from the "Off" position if the locking mechanism is in the locked position. If the locking mechanism is operated when the ignition switch is in an operative position, the ignition drum will be locked upon its return to initial or "Off" position.

The locking mechanism is provided with a wedge member which disconnects the lighting drum from its associated operating handle. Accordingly, whenever the lock is moved to the locked position, the lighting switch handle is disconnected from the lighting drum, and further operation of such drum is prevented until the locking mechanism is moved to the unlocked position.

Fig. 1 is a plan view of a switching mechanism constructed in accordance with my invention; Fig. 2 is a sectional view of the switching mechanism shown in Fig. 1; Fig. 3 is a sectional view along the line III—III of the switching mechanism shown in Fig. 2, and Fig. 4 is a similar sectional view along the line IV—IV of Fig. 2, and Fig. 5 is a detailed view of the spring member for actuating the positions of the drums.

Referring to the drawing, a casing 1, of any suitable metallic material, is attached to a base member 2. The base member 2 may be mounted upon the dash-board of an automobile in any suitable manner. Plates of insulating material 3 are mounted upon the base of the casing 1 for supporting the various contact terminals of the switching mechanism. If so desired, the casing 1 may be composed of any suitable insulating material.

A rod 4, which extends through the base 2 and the casing 1, supports an ignition switch drum 5 and a lighting switch drum 6. The drum 5 is fixedly mounted on the rod 4, whereas the drum 6 is rotatably mounted on such rod. An ignition switch handle 7 is connected to the rod 4 by a pin 8 or any other suitable means and serves to effect operation

of the ignition drum. A flanged cylinder 9 is positioned between the drums 5 and 6 and the handle 7, and a washer 10 is mounted outside the plates 3 near the end of the rod 4 for maintaining the drums 5 and 6 and the rod 4 in position.

A handle 11 is mounted on the cylinder 9 between the base plate 2 and the ignition handle 7 and serves to control the operation 10 of the lighting drum 6. The lighting switch handle 11 is connected, in any suitable manner, to a collar member 12 which is located on the opposite side of the base plate 2 and which is rotatably mounted upon the cylinder 9.

A spring member 13 is rigidly connected to the collar member 12 and is provided with a pin 14 for entering a recess 15, formed in the lighting drum 6. The spring member 20 13 is provided with a projecting portion 16 for a purpose to be hereinafter set forth. A washer 17, of any suitable insulating material, is disposed between the two drums 5 and 6 and a second washer 18 is located 25 between the ignition drum 5 and the insulating disc 3, which is mounted on the base of the casing 1.

The lighting drum 6 is provided with a contact segment 19 which is moved into engagement with the contact fingers 20, 21 and 22, according to the operative position of such switch. Notches 23 are formed in the periphery of such drum and are engaged by a bowed spring member 24 for accentuating 30 the various switch positions. The drums 5 and 6 may be composed of any suitable insulating material.

The ignition drum 5 is provided with a contact segment 25 which is adapted to 40 bridge the contact fingers 26 and 27 when the ignition switch is in an operative position. Two notches 28 are formed in the periphery of the drum 5 and co-operate with a bowed spring member 29 for accentuating 45 the "On" and the "Off" position of the ignition switch. A recess 30 is formed in the periphery of the ignition drum for a purpose to be hereinafter set forth.

A locking mechanism 31, preferably of 50 the Yale or Corbin type, is provided for locking the ignition drum in the "Off" position and for disconnecting the lighting drum from its associated handle in any position of the lighting drum. The locking 55 mechanism is mounted in a cylinder 32 which is located within the casing 1. A key 33 is provided for operating the locking mechanism and for effecting rotation of a cylinder 34. The tumblers, (not shown), of 60 the locking mechanism prevent rotation of the cylinder 34 within the cylinder 32 except when the key 33 is inserted in position. Inasmuch as my invention does not involve 65 the specific construction of the lock itself a detailed description of such lock is omitted.

A wedge member 36, which is mounted upon the cylinder 34 and which projects through the cylinder 32, is adapted to engage the projection 16 of the spring member 13 and to raise the pin 14 from the recess 15 in the drum 6 whenever the locking mechanism is moved to a locked position. The wedge member 36 is of such size, as shown in Fig. 4, as to effect operation of the spring member 13 for disconnecting the drum 6 from the handle 11 no matter what the operative position of the lighting drum may be.

A block or pin member 38, which projects through an opening rear the end of the cylinder 32, is adapted to enter the recess 30 80 in the drum 5 when such drum is in its "Off" position and the locking mechanism is in the locked position. The cylinder 34 is provided with a cam-shaped end portion 39 which co-operates with a groove 40 in the block 38 for adjusting the position of such block. The block 38 is biased to the raised or locked position by a spring member 41, as shown in Fig. 3 of the drawing. The locking mechanism is shown in the locked 90 position. Upon rotation of the key in a clockwise direction to the unlocked position, the cam-shaped end portion 39 of the cylinder 34, operating within the groove 40 of the block 38, lowers such block away from 95 the ignition drum 5.

In a switch mechanism constructed as above set forth, it is apparent that the ignition drum may be locked in the "Off" position and the lighting drum may be rendered inoperative no matter what position may be occupied by it. Moreover, the locking mechanism may be operated when the ignition drum is in an operative position to prevent further operation of the lighting 100 drum and to effect locking of the ignition drum when it is returned to the "Off" position.

Modifications in the mechanism and in the arrangement and location of parts may be 110 made within the spirit and scope of my invention, and such modifications are intended to be covered by the appended claims.

I claim as my invention:

1. In a switching mechanism, the combination with two switch drums, and a handle for operating each of said drums, of means comprising a locking device for locking one of said drums in the "Off" position thereof and for disconnecting the second 120 drum from its associated handle in any operative position of said second drum.

2. In a switching mechanism, the combination with two switch drums, and a handle operatively connected to each of said 125 drums, of a member for engaging one of said drums in the "Off" position thereof, a member for disconnecting the second drum from its associated handle in any position of said second drum and a locking device for con- 130

trolling the operation of said engaging member and said disconnecting member.

3. In a switching mechanism, the combination with two switch drums mounted 5 for rotation about the same axis and a handle operatively connected to each of said drums, one of said drums having a recess therein, of a member for entering said recess to lock said one drum against rotation, a 10 member for disconnecting the other drum from its associated handle, and a locking device for operating said locking member and said disconnecting member.

4. In a switching mechanism, the combination with an ignition drum having a 15 recess therein, an element biased to enter said recess when the ignition drum is in the "Off" position, a handle for controlling said drum, a lighting drum rotating about the 20 same axis as said ignition drum, a handle for said lighting drum, and a spring connection between the lighting drum and its associated handle, of a member for operating said spring connection to disconnect the 25 lighting drum from its handle and a locking mechanism for controlling said element and the disconnecting member.

5. In a switching mechanism, the combination with an ignition drum, a handle for 30 operating the ignition drum, a lighting drum and a handle for operating the lighting drum, of means comprising a pin for locking the ignition drum only in the "Off" 35 position thereof, and a wedge member for rendering the lighting handle ineffective in any position of the lighting drum.

6. In a switching mechanism, the combination with two drums, and a handle for 40 operating each of said drums, of means for locking one of said drums only in the "Off"

position thereof and for rendering the handle of the second drum ineffective when said drum is in any position.

7. In a switching mechanism, the combination comprising two rotatable switch 45 members having the same axis of rotation, a handle for operating each of said drums, and means for locking one of said switch members in the "Off" position thereof and for preventing operation of the second 50 switch member by its associated switch handle when said second switch member is in any position.

8. In a switching mechanism, the combination comprising two switch members 55 having the same axis of rotation, a handle for operating each of said switch members, and means for locking one of said switch members only in the "Off" position thereof and for preventing operation of the second switch member when it is in any position. 60

9. In a switching mechanism, the combination with two switch drums having a common axis of rotation, of means for locking one of said drums in the "Off" position thereof and means for preventing operation 65 of the second drum when the first drum is in any position.

10. In a switching mechanism, the combination with two switch drums having a common axis of rotation, of locking means 70 for preventing operation of either switch drum from the "Off" position and for preventing movement of one switch drum from any occupied position when the other drum is in any position. 75

In testimony whereof, I have hereunto subscribed my name this 30th day of July, 1920.

WARREN P. LOUDON.
